UNITED STATES PATENT OFFICE.

FRED BUCK, OF SAGINAW, MICHIGAN, ASSIGNOR TO THE LUFKIN RULE COMPANY, OF SAGINAW, MICHIGAN, A CORPORATION OF MICHIGAN.

TAPE-MEASURE.

1,170,956.

Specification of Letters Patent.

Patented Feb. 8, 1916.

Application filed December 19, 1914. Serial No. 878,051.

To all whom it may concern:

Be it known that I, FRED BUCK, a citizen of the United States, and a resident of Saginaw, county of Saginaw and State of Michigan, have invented a new and useful Improvement in Tape-Measures, of which the following is a specification, the principle of the invention being herein explained and the best mode in which I have contemplated applying that principle, so as to distinguish it from other inventions.

The present improvements relate in general to tape measures and in particular to that type of tapes which are formed of steel, or other breakable material, and are housed in a case. In this style of tapes considerable difficulty has been experienced from breakage of the tape proper, and in about three fourths of such cases the break has occurred at a point an inch or two from the free end of the tape, being caused by a slight unwinding of the tape when carried in the pocket of the user which results in breakage if struck against some outside object or if bent excessively when the tape is withdrawn from the pocket.

It is therefore the object of the present invention to provide means for normally maintaining the tape within the casing, such means being also designed to permit of easy manipulation by an operator when it is desired to unwind the tape.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—Figure 1 is a side elevation of a tape measure in which are embodied my present improvements, being sectioned adjacent to the slot through which the tape passes; Fig. 2 is a view similar to Fig. 1 but showing the tape end raised to permit of unwinding, and Fig. 3 is a perspective view of the frame or throat which is mounted in the casing and bounds the slot.

In Fig. 1 there is shown a casing 1 of the usual form provided internally with a winding element 2 which may be operated by the usual pivoted handle mounted externally of

the casing. The casing is also provided with a peripheral slot 4 through which the free end of a tape 5 passes, the tape being attached at its other end to the winding element.

The peripheral slot 4 is bounded by a metal frame or throat 6 which is set into the casing and is provided adjacent to one end with a roller 7 for holding the tape 5 against the opposite end of the throat. A preferred form of the means which I employ for maintaining the tape within the casing when wound, consists of coöperative means mounted on the casing and on the free end of the tape and adapted to automatically engage when the tape is wound in. Such means consists of a recess 10 formed in the downwardly or inwardly projecting flange 3 of the throat in which there is adapted to engage a latch in the form of a button 8 attached to the under side of the tape adjacent to the end.

Upon winding in the tape the same is brought entirely within the slot and therefore within the casing with the exception of the hook or finger hole 9 attached to the free end of the tape, such hook 9 being broader than the slot and thereby preventing the end of the tape from being wound into the casing. The resiliency of the tape and the position of the roller 7 causes the tape to lie against the opposite end of the throat and thus any outward movement of the tape will cause the button 8 to engage in the recess 10 in the throat, thus locking the tape in its wound up position. The manner in which an operator can release this engagement between the button and the recess is illustrated in Fig. 2 and it will be noticed that the only thing which must be done is for the operator to grasp the hook and raise the tape slightly away from the raised end of the throat when the tape can be drawn out as in the ordinary construction.

I have found that the aforesaid means effectually maintain the tape within the casing until released by the user and in this way eliminate the cause of three fourths of the breaks which have been so frequent in the past. The addition of these or similar means to a tape adds but slightly to the cost and in no way limits the usefulness of the tape or the simplicity and ease of manipulation.

110

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

- 10 1. In a tape measure, the combination with a casing having a winding element therein and having also a peripheral slot for the passage of the tape, of a resilient tape attached at one end to said winding element and having its other end extending through such slot, a guide normally maintaining said tape against one end of such slot, and means mounted adjacent to such end of such slot and on said tape and adapted 20 to inter-engage when said tape is wound in and to thereby prevent accidental unwinding of the same through such slot.
- 25 2. In a tape measure, the combination with a casing having a winding element therein and having also a peripheral slot for the passage of the tape, of a resilient tape attached at one end to said winding element and having its other end extending through such slot, a guide normally maintaining said tape against one end of such

slot, and coöperative means mounted on the free end of said tape and on said casing adjacent to such end of such slot, said means being adapted to prevent the free end of said tape from accidental movement 35 through and beyond such slot after said tape has been wound in.

3. In a tape measure, the combination with a casing having a winding element therein and having also a peripheral slot 40 for the passage of the tape, and a tape attached at one end to said winding element and having its other end extending through such slot, of a frame set into said casing about the edges of such slot, and having a 45 recess in one edge adjacent to the path of movement of said tape, and a button mounted upon the under side of the free end of said tape and adapted to be automatically engaged in such recess upon the winding in 50 of said tape and thereby preventing accidental outward movement of said tape through and beyond such slot.

Signed by me, this 16th day of December, 1914.

FRED BUCK.
